LOADING MACHINE

Nils D. Levin, Columbus, Ohio, assignor to The Jeffrey Manufacturing Company, a corporation of Ohio

Original application October 22, 1937, Serial No. 170,426. Divided and this application January 17, 1941, Serial No. 374,823

1 Claim. (Cl. 198—7)

This invention relates to loading machines, and one of the objects of the invention is the provision of an improved and efficient frontal attack type of loading machine adapted for the loading of coal in a coal mine particularly while still standing in a semi-compact mass at the coal face after having been shattered or dislodged from the solid of the mine vein by blasting charges.

Another object of the invention is the provision of a main frame so combined with a gathering conveyor unit and a discharge conveyor unit as to provide for a minimum of stress and strain during operation.

Still another object of the invention is to provide in a loading machine adjusting, operating and controlling means all driven from a common motor.

Another object of the invention is to reduce the overall height of a loading machine by providing improved and efficient adjusting, operating and controlling means all driven by a single electric motor on the main or supporting frame.

Other objects of the invention will appear hereinafter, the novel features and combinations being set forth in the appended claim.

In the accompanying drawings,

Fig. 1 is an elevational view of the loading machine comprising my invention with the swinging boom of the discharge conveyor cut short;

Fig. 2 is a vertical longitudinal sectional view of the loader with the rear end of the discharge conveyor cut off and with the forward end of the gathering conveyor cut off;

Fig. 3 is a sectional plan view showing the forward end of the truck, the drive means for the gathering conveyor, and the truck propelling mechanism at the rear end of the truck;

Fig. 4 is a transverse sectional elevational view taken on the line 4—4 of Fig. 2, looking in the direction of the arrows; and

Fig. 5 is a transverse sectional elevational view of the discharge conveyor driving mechanism.

This application is a division of my co-pending application, Serial No. 170,426, filed October 22, 1937, for an improvement in a loading machine.

As illustrated generally in Fig. 1 of the drawings, the mining and loading machine comprising my invention is primarily a frontal attack machine but provision is made whereby a gathering conveyor cannot become wedged into the material being loaded in that the attack is not confined to a frontal attack but also includes a lateral attack at both sides of the forward end of the gathering conveyor.

The said loading machine comprises a track mounted truck 40 upon which is mounted a gathering conveyor 41 and a discharge conveyor 42, the former being adapted to dig into and gather loose or semi-compact coal and to convey it to the latter by which it is discharged into track mounted coal cars.

Power means is provided to tram the loading machine along a mine track at a relatively fast speed, and to operate it along said track at a feeding or operating speed while at the same time operating the gathering and discharge conveyors to gather and load coal into coal cars.

The truck 40 comprises a main frame formed by longitudinally extending side members 44 rigidly attached together at their forward ends by an arcuate front cross-piece formed by spaced members 45.

Adjacent its forward end, the main frame comprises a bed plate 49 (Fig. 2) rigidly attached to the tops of the side members 44 and front cross-pieces 45, as by welding. The gathering conveyor 41 and the drive means therefor are supported from this bed plate 49.

Adjacent its rear end the main frame is provided with a bed plate 50 (Fig. 2) which is rigidly attached to the bottoms of the side members 44. The bed plate 50 supports the single drive motor 224 which drives all of the apparatus on the loading machine, and supports most of the gear mechanism for controlling said loading machine.

The truck 40 is mounted upon a pair of forward track engaging flanged wheels 51, 51 keyed on axle 52 which is journaled in adjustable bearing boxes 53, 53 slidably supported upon guideways 54, 54. Gearing mechanism 55 is provided for adjusting the bearing boxes 53, 53 in unison longitudinally along the guideways 54, 54 from a convenient position adjacent the side of the truck 40.

The truck 40 is also provided with rearward track engaging flanged wheels 56, 56 mounted upon axle 57 journaled in bearing boxes 58, 58 (see Fig. 3) slidably longitudinally in guideways.

Gearing mechanism 61 readily accessible from the side of the truck 40, as best seen in Fig. 3, is provided for adjusting the bearing boxes 58, 58 longitudinally in unison along the guideways 60.

The axles 52 and 57 are provided with sprockets 50 which are connected together by a continuous chain 65 to insure their movement in unison. Axle 57 also carries a drive sprocket 59 by which it is driven. It is thus evident that driving power will be applied to all of the track engaging wheels 51, 51 and 56, 56.

The construction of the gathering conveyor 41 comprises a turntable 68 formed by a bottom plate 69 provided at its rear end with a circular opening adapted to receive a journal bearing 70 (Fig. 2) which is reinforced by a plate 71 and a ring 72, all rigidly attached together, as by welding. The journal bearing 70 is journaled to a casting 73 which is removably attached to the front bed plate 49 by virtue of screws 74 which thread into a ring 75 welded to the bottom of said front bed plate 49, as clearly seen in Fig. 2 of the drawings. It is thus evident that the turntable 68 is journaled to the truck 40 about an upright axis provided by the casting 73 thereby providing for lateral swinging movement of the gathering conveyor 41.

It will be evident that the thrusts received by the gathering conveyor 41 will be translated to the truck 40 through the casting 73 and thus this casting and the journal bearing 70 associated therewith is made of very rugged construction.

As clearly illustrated in Fig. 2 of the drawings, the bottom plate 69 is removably attached to the casting 73 by a threaded ring 76 threaded to the top of said casting 73 and held locked by a set screw 77.

The turntable 68 also includes upright side plates 78 and intermediate front plates 79 which cooperate to support a top plate 80, which plates co-operate to provide a gearing housing and support, as hereinafter explained in full detail.

Side plates 78 of the turntable 68 carry side brackets 81, 81 provided with pivot pins 82 upon which is pivoted the gathering boom 83 of the gathering conveyor 41 by means of brackets 84 (Fig. 1) having apertures to receive the pins 82, which brackets 84 are welded rigid with side members 85 of said gathering boom 83. It will be evident that the boom 83 is swingable with respect to the turntable 68 about a horizontal axis provided by the pivot pins 82. The gathering boom 83 comprises a bottom plate 86 welded to a cross I-beam 101 (Fig. 2) which said bottom plate 86 is welded rigid with the side members 85, 85 and, at its rear end, is substantially parallel with and forms an extension of the top plate 80 of turntable 68.

The bottom plate 86 carries a pair of gathering chain guides each formed by an outer grooved track member grooved at its outer surface to receive the side bars and retaining gibs of the gathering conveyor chains designated generally 91. That is, the track members are provided with grooves and retaining flanges to keep the gathering conveyor chains 91 in proper position.

The track members extend substantially the full length of the gathering conveyor 41 and thus the gathering conveyor chains operate substantially through the entire length of said gathering conveyor. As a consequence, there is only one re-handling of the gathered material from the time it is first gathered by the gathering conveyor to the time it is discharged into the mine cars and this is during the time it is discharged from the gathering conveyor to the discharge conveyor.

Since the gathering boom 83 of the gathering conveyor 41 is pivoted about a horizontal axis 82 with respect to the turntable 68 of said gathering conveyor 41, it is, of course, evident that the track members 90 must be broken at this pivot point. As illustrated in Fig. 2 of the drawings, an extension for the track members is provided at 97 to guide the conveyor chain 91 in its movement over the turntable 68. The extensions

97, of which there will be one for each of the two gathering conveyor chains, provide guide paths on each side thereof leading both to and from drive sprockets 98 for which there will be one for each of the chains 91. The extensions 97 will, of course, terminate the guide track for the chains 91 adjacent the drive sprockets 98.

Each of said extensions 97 is provided with a rounded nose 99 (Fig. 2) adapted to extend into a pocket in the frame of the boom 83 and slightly spaced therefrom. This, of course, permits limited movement of the boom 83 about the horizontal axis provided by the pins 82. It is also to be noted that protecting cover plates 100 are provided adjacent and above the top plate 80 of the turntable 68, which cover plates 100 overlap the cover plates 95. (Fig. 2.)

To provide for the swinging of the gathering conveyor 41 about the vertical axis of casting 73 I provide a very simple and compact arrangement in the form of a hydraulic piston motor 134, best seen in Fig. 3 of the drawings, comprising a cylinder 135, pivotally attached at its rear end to a bracket 136 formed rigid with the main frame of the truck 40, and a piston carrying a rod 137 pivotally attached to a bracket formed rigid with the turntable 68 of the gathering conveyor 41. The piston motor 134 is of the double acting type. That is, it may be moved under power in reverse directions and with the system comprising my invention, may be locked in any adjusted position, as hereinafter described. It is to be noted that this hydraulic piston motor 134 is entirely within the confines of the loading machine truck 40 and thus does not increase the width of said machine. It is furthermore to be noted that it is highly protected and therefore cannot be easily damaged.

I pivotally attach to every sixth main link a gathering flight 143 interspersed with alternate gathering flights 144. The essential difference between the gathering flights 143 and 144 lies in the fact that the former carry removable bits or picks 145 which are particularly effective to dig into and break down a semi-compact mass of material while the gathering flights 144 are devoid of such bits or picks.

Attention is now directed particularly to the construction of the discharge conveyor 42 as illustrated in Figs. 1 and 2. Said discharge conveyor 42 comprises three articulated parts including a stationary hopper 155 supported upon the front bed plate 49 of the truck 40 by spaced side brackets seen at 156 in Fig. 5 of the drawings. The hopper 155 is removably attached to the side brackets 156 by nuts and bolts 157. The hopper 155 comprises spaced side members 158 and a downwardly inclined rear chute 159 (Fig. 2) formed integral with said side plates 158. The chute 159 is adapted to receive coal as it discharges from the rear end of the gathering conveyor 41 over the top plate 80. A guiding arcuate apron 160 is carried by the top plate 80 in overlapping relation with the chute 159 to insure the proper reception of coal by said hopper 155 without any loss thereof. The chute 159 is of generally conical form thus permitting free rotation of the apron 160 with respect thereto.

It may also be pointed out that the side plates 78 of the turntable 68 have rearwardly extending deflector wings 161, 161' which extend over and partially into the arcuate chute 159 of the hopper 155 thus guiding the material discharged by the gathering conveyor 41 into the hopper 155. (Fig. 2.) The hopper 155 is provided with a

chain guiding bottom plate 162 (Fig. 2) which is primarily adapted to guide the return flight of the conveyor chain associated with the discharge conveyor 42. A feed plate 163 is provided adjacent the forward end of the chute 159 in the hopper 155 and feeds the material onto a material supporting false bottom plate 164 of the hopper 155 over which bottom plate 164 the upper run of the flight carrying conveyor chain 165 of the discharge conveyor 42 travels to convey the coal rearwardly and discharge it into the mine cars.

Pivottally attached to the hopper 155 by means of spaced side brackets 166, 166 (Fig. 2) carried by side members 167 and journaled on pins 168 is a discharge boom 169. It is evident that the boom 169 is pivoted about a horizontal axis formed by pins 168 for vertical swinging movement with respect to the hopper 155 and the truck 40. At the forward end of the discharge conveyor 42 (see Fig. 2) I provide within the hopper 155 a centrally disposed guide sprocket 188 for said chain 165.

To effect a driving of the chain 165 I provide a drive sprocket 189 mounted on a shaft 190 which is journaled in the rear end of the side members 158 of the hopper 155. To maintain the chain 165 in meshing relation with the drive sprocket 189 I provide a curved wear shoe 192 mounted on the false bottom plate 164.

As clearly illustrated in Figs. 1 and 5 of the drawings, the chain 165 carries a plurality of spaced flights 193 which, during the upper run of the chain 165 are adapted to scrape over the false bottom plate 164, thereby to convey material rearwardly from the hopper 155 and discharge it into the mine cars.

Attention is now directed particularly to Figs. 2 and 4 and to the drive means for the various devices to be driven. At the outset it may be stated that only a single or common electric motor 224 is relied upon as the primary source of power to effect a driving of all of the devices of the loading machine. Said electric motor 224 is mounted upon the rear bed plate 50 of the truck 40 and compactly positioned below the discharge conveyor 42 which extends upwardly and rearwardly from the hopper 155. In Fig. 2 only the forward end portion of electric motor 224 is shown but it should be understood that this motor is relatively large and may extend rearwardly together with the bed plate 50 to the extent shown in my Patent No. 2,303,372, granted December 1, 1942, for an improvement in a loading machine. Due to this positioning of the electric motor 224 it is possible to provide a very large and powerful motor which is capable of effecting any and all of the drives required at any time while maintaining a machine of low height to permit its use in a relatively low head coal mine. Said electric motor 224 is provided with a forwardly extending armature shaft 225 (see Fig. 2) carrying a drive pinion 226 meshing with a bevel ring gear 227 which is rigidly attached to the housing 228 of a friction clutch mechanism 229. The housing 228 is keyed to a vertical shaft 230 which is mounted at its top in a bracket 231 rigidly attached to the main frame of the truck 40, there being an anti-friction ball bearing 232 interposed between the bracket 231 and the shaft 230 which is held in place by a removable cap 233. The bottom of the shaft 230 is supported in a bracket 234 (Fig. 4) formed rigid with the bottom plate 50, said support being through an anti-friction ball bearing 235. Keyed to the lower end of the shaft 230 and above the bearing 235, is a bevel gear 236. It may

thus be noted that the gear 227 and the gear 236 being both keyed to the shaft 230, will be driven together at all times from the motor 224.

Journaled loosely on the central portion of the shaft 230 is a clutch member 237 (Fig. 4). Splined on the interior of the housing 228 and on the exterior of the clutch member 237, which members 228 and 237 comprise cooperating clutch members, is a plurality of overlapping stacked friction plates 238, alternate ones of which are connected to the housing 228 and the clutch member 237, respectively. Adjacent its bottom the clutch member 237 is provided with an integral extended flange 239 to which is pinned a gear 240. The flange 239, in addition to supporting the gear 240, also acts as one compression member for the friction clutch plates 238.

To effect a compression of the clutch plates 238 (Fig. 8) and thus to effect an engagement of the clutch elements 228 and 237, I provide a compression ring 241 within the housing 228 having a flange which bears against said plates 238. Downward movement of the ring 241 to effect the aforementioned compressing action is effected by a plurality of pins 242 which extend through apertures in the housing 228 and are carried by a ring 243 operable through an anti-friction ball bearing 244 operable by a trunnion collar 245 which is controlled by a shipper 246 keyed on a shaft 247 (Fig. 4) which shaft 247 is journaled at one end in an upwardly extending plate rigidly attached to the main frame of the truck 40.

Adjacent its other end the shaft 247 is supported in a pair of downwardly extending apertured plates 250, 250 (see Fig. 4) which are bolted to the bracket 231.

It will be evident that rocking movement of the shaft 247 to urge the collar 245 (Fig. 4) downward will cause an application of the friction clutch 229 to drive the gear 240 and when the shaft 247 is released the clutch 229 will automatically become disengaged due to lack of sufficient clamping pressure on the plates 238.

It may be stated that the gear 240 which is controlled by the clutch 229 is individual to a gear train for driving the gathering conveyor chains 91. The gear 240 meshes with idler gear 251 mounted upon an anti-friction supported shaft 252 journaled in a cup 253 rigidly and removably attached to front bed plate 49, which gear 251 in turn meshes with a large gear 254 carried by a shaft 255 on anti-friction bearings in the previously described casting 73.

It is to be particularly noted that since the vertical axis about which the gathering conveyor 41 swings is along the axis of the shaft 255, power can be transmitted to said gathering conveyor through the gear 254 while the gathering conveyor is in any desired position of adjustment. The large gear 254 meshes with one of a pair of intermeshing large gears 256, 256 (Fig. 3) which are journaled in the bottom plate 69 and top plate 89 of the turntable 68 and which drive the previously mentioned sprockets 98 through shafts 257, 257. It is thus seen that the two drive sprockets 98 are driven in reverse directions and at the same speeds, thereby to drive the gathering chains 91 at the same speeds and in reverse directions, with the flights on one chain in fixed relation to the flights on the other chain.

Attention is now directed particularly to Figs. 2, 3 and 4 and to the gear train which is operative to drive the truck 40 either forwardly or reversely and at either a fast trammimg or transportation speed or at a low feeding or sumping speed. This

gear train includes the previously described gear 236 which, as above pointed out, is driven directly from the motor 224. Gear 236 meshes on opposite sides with bevel gears 258, 258 of reversing friction clutches 259 and 260, respectively, as shown in Fig. 4.

Except in a respect hereinafter described in full detail, the clutches 259 and 260 are similar and thus a detailed description of clutch 259 will suffice for both. Said clutch 259 comprises a housing 261 to which the bevel gear 258 is keyed. The housing 261 is loosely journaled on a longitudinally extending hollow drive shaft 262 to which is keyed the clutch member 263. Housing 261 and clutching member 263 carry alternate stacked friction clutch plates 264 which may be compressed into clutch engaging position by an operating ring 265 adapted to be engaged by the opposed heads of an operating key 266 which extends through an elongated slot 267 in the drive shaft 262 and through an elongated slot 268 in an operating shaft 269 and is removably held in place by said end heads, one of which is formed by spaced bars 265 rigidly and removably attached by rivets 266. It will be evident that the bevel gears 258 rotate the housings of the clutches 259 and 260 in reverse directions. Consequently, when clutch 259 is applied shaft 262 will rotate in one direction and when clutch 260 is applied it will rotate in the reverse direction.

The elongated slots 268 are so spaced with respect to the operating shaft 269 that both of said clutches 259, 260 may be in released condition at the same time and when the shaft 269 is shifted to the right, as viewed in Fig. 4, the clutch 260 will be applied and when shifted to the left, the clutch 259 will be applied.

The reverse ends of the shaft 262 are mounted in appropriate journal bearings one of which is shown at 271 (Fig. 4), both bearings being formed rigid with the false bottom plate 249.

Keyed to the shaft 262 is a drive pinion 272 which drives a variable speed reduction mechanism comprising a gear 273 constantly in mesh therewith, which is keyed to a pinion 274 both of which are journaled loosely upon a countershaft 275 mounted for free rotation in spaced journals and a thrust bearing carried by the false bottom plate 249, the latter of which prevents axial movement of shaft 275. Pinion 274 meshes with a gear 278 keyed to a pinion 279 and mounted upon a shaft 280 (Fig. 3) journaled in bearings 281, 281. Pinion 279 meshes with a gear 282 which is also loosely journaled on countershaft 275.

The gears 273 and 282 are provided with clutch jaws 283 and 284 respectively, which cooperate with clutching elements 285 and 286, respectively, having appropriate cooperating jaws. A shipper 287 is provided for the clutching elements 285 and 286, which shipper is adjustably mounted on a shiftable shaft 288 slidable at one end in a journal 289 carried by side plate 44 and at the other end pivoted to an operating lever.

If the shaft 288 is moved in one direction, clutching element 285 will be moved to engaged position which will effect a high speed connection between the drive shaft 262 and the countershaft 275. When the clutching element 286 is moved into engaged position by moving the shaft 288 in the opposite direction, a low speed connection will be effected between the drive shaft 262 and the countershaft 275.

Keyed to the countershaft 275, is a drive sprocket 293 which drives the sprocket 59 (see

Fig. 3) through a drive chain 293'. As was previously pointed out, the drive sprocket 59 drives the axle 57 and the wheels 56, 56 of the truck 40, which axle 57 in turn drives the axle 52 through the chain 65 to drive the wheels 51, 51 of the truck 40. It is thus manifest that the loading machine may be driven through the traction wheels 51, 51 and 56, 56 from the motor 224 either forwardly or reversely at either a high transportation speed or a low feeding speed without requiring reversal of the direction of rotation of said motor 224. It is also obvious that the motor 224 may be operated without requiring movement of the loader along the mine track.

Attention is now directed particularly to Figs. 2, 4 and 5 and to the gear train for driving the conveyor chain 165 associated with the discharge conveyor 42. This gear train includes a novel arrangement in which the housing 261 of the clutch 259 is employed as a direct tubular drive element. This arrangement is described and claimed in my co-pending application S. N. 445,834, filed June 5, 1942, for an improvement in Loading machines. As clearly seen in Fig. 4 of the drawings, the housing 261 has rigidly attached to it a cover plate 295 having a neck 296 which is journaled loosely on the drive shaft 262 to which neck 296 is keyed a drive sprocket 297. The cover plate 295 is removably attached to the housing 261 by machine screws 298. It is thus evident that motion of the gear 258 associated with clutch 259 will be transmitted directly to the sprocket 297 through the housing 261 and cover plate 295.

The drive sprocket 297 drives a sprocket 301 through a chain 302 (see Figs. 4 and 5) which sprocket 301 is rigidly attached to a friction clutch housing 303 which drives the clutch member 304 through stacked friction plates 305 operable by clamp ring 306 by a shipper ring 307 operating through a ball thrust bearing 308 and controlled by a shipper cooperating with trunnions 309 on the ring 307. The said shipper comprises spaced top and bottom bars 310, 310 pivoted to the trunnions 309, 309.

It is also to be pointed out that a single electric motor is provided for operating the entire loading machine including the providing of fluid pressure for the hydraulic control system. No auxiliary electric motor of any kind is required on the loading machine comprising my invention.

A general review of the construction and operation of the mining and loading machine shown in the accompanying drawings will show more clearly the flexibility of adjustments to obtain the most efficient operation in mining and loading coal by attacking a semi-compact mass of coal shot down from the face of a coal vein. When the gathering conveyor is in the full line position shown in Fig. 1, the whole machine may be transported along the mine track under the control of the operator who may start or stop the electric motor 224 of Fig. 2. By means of a lever the operator may reverse the electric motor 224 and thereby control the direction of travel of any of the conveyor chains should they become stuck.

The truck propelling means comprises power transmission mechanism between the electric motor 224 and all of the wheels 51 and 56 of the truck, as shown in Figs. 2 and 3. This power transmission mechanism is under the control of the clutch 229 shown in Figs. 2 and 4. The operator may apply or release the clutch 229 by means

of a lever. The truck propelling power transmission mechanism also includes reversing clutches 259 and 260 shown in Fig. 4, either of which may be applied by the operator actuating a lever in one direction or the other, and consequently the loading machine during operation may be moved along the mine track in either direction without reversing the electric motor 224.

When the shaft 262 of Fig. 4 is rotated in one direction or the other, the pinion 272 thereon drives the reduction gearing shown in Fig. 3, which is under the control of the clutches 285 and 286 for the purpose of securing relatively low speed and relatively high speed of transmission to the transverse shaft 275 shown in Fig. 3. A sprocket chain drive comprising the sprocket 293 on the shaft 275, connects the shaft 275 with the axle 57 shown in Fig. 3. It will thus be seen that the electric motor 224 may be continuously operated in the same direction while by means of the clutches 259 and 260 in Fig. 4 the gathering mechanism may be moved forwardly or rearwardly under the control of the operator, and such forward or rearward movement may be at relatively fast speed or at relatively slow speed under the control of the clutches 285 and 286 of Fig. 3. A slow powerful sumping movement into the semi-compact mass of shot down coal may thus be effected, and whenever desired a slow, powerful withdrawal movement of the gathering mechanism may also be effected.

The power transmission mechanism connected between the motor 224 and the pair of endless conveyor chains on the gathering device 41, comprises the gear 240 on the vertical shaft 230 of Fig. 4. The gear 240 meshes with the gear 251 which in turn meshes with the gear 254, and the latter is in mesh with one of the gears 256 as shown in Fig. 3. Since the gears 256 mesh with each other, the flights of the gathering conveyor are in such fixed relation to each other that they travel in pairs, in opposite directions. The starting and stopping of the pair of endless chains of the gathering conveyor are controlled by the clutch 229 shown in Figs. 2 and 4. During normal operation of the gathering conveyor the flights move in pairs towards the discharge conveyor 42 and therefore the motor 224 should be continuously operated in the same direction. Should a lump of coal get caught between the rear end portion of the gathering conveyor and the roof of the mine chamber, the crowding and wedging action will be downward against the upwardly extending serrations of the flights 143, 144 and against the points of the cutter bits 145, thereby effecting a crushing of the unusually large lump of coal so that delivery of the coal to the discharge conveyor need not be interrupted. If there is an overload on the gathering conveyor chain 91 due to contact between flights 143 or 144 and solid or irremovable coal the friction clutch 229 will slip, whereupon the proper clutch 259 or 260 will be operated to cause the machine to move rearwardly thereby causing the conveyor flights 143 and 144 to release the contacted coal and relieve the overload.

Under the control of a lever, the operator may control the swinging of the gathering conveyor laterally on its vertical pivotal connection at 255 (Figs. 4, 5) to the truck frame 44, and during such lateral swinging movement of the gathering conveyor its supporting frame 68 rests at its forward end on the rollers 128, as shown in Fig. 3. A single reciprocating hydraulic motor 134, pivotally connected at its ends to the truck frame

and the gathering conveyor frame, is relied on to swing the forward end of the gathering conveyor laterally to various angular positions relative to the mine track. The gathering conveyor may be locked by means of the motor 134 in its angular adjusted position when the loading machine is to be sumped or withdrawn rectilinearly parallel to the mine track, but it should be understood that the reciprocating hydraulic motor 134 is sufficiently powerful to swing the forward portion of the gathering conveyor in either direction for lateral attack on a semi-compact mass of shot-down coal, and at various elevations illustrated in full and dotted lines in Fig. 1.

15 The discharge conveyor is connected by means of the sprocket and chain gearing 301, 302, 297 to the shaft clutch housing 295 and bevel gear 258 as shown in Figs. 4 and 5. By applying the clutch 229 power transmission mechanism is connected between the motor and the sprocket 297 to drive the sprocket chain 302 directly from the motor 224 independently of the operation of the truck propelling mechanism. By applying the clutch 303, 304, 305 (Fig. 5) the sprocket chain 302 will be connected to the discharge conveyor. It will thus be seen that the motor 224 may drive both the gathering conveyors and the discharge conveyor always in the same direction while the entire loading machine may be reciprocated along the mine track during loading operations by applying the clutches 259 and 260 (Fig. 4) alternately.

The general combinations including various adjustments of the gathering and discharge conveyors, and the extension control for the discharge mechanism from two points, are covered by claims in the parent application S. N. 170,426, filed Oct. 22, 1937, for an improvement in Loading machines. The gathering conveyor including the specific gathering flights is described and claimed in my copending application S. N. 305,803, filed Nov. 24, 1939, for an improvement in Loading machines. The apparatus for propelling the loading machine and for reciprocating the same during loading operations including reverse friction clutch mechanism is disclosed and claimed in my co-pending application S. N. 377,349, filed Feb. 4, 1941, for an improvement in Loading machines. The hydraulic system of operation and control including the extensible hydraulic motors is described and claimed in my co-pending application S. N. 379,475, filed Feb. 18, 1941, for an improvement in Loading machines. The structure embodying the three-point support is disclosed and claimed in my co-pending application S. N. 380,880, filed Feb. 27, 1941, for an improvement in Loading machines. The apparatus for effecting operation of the cable reel in connection with the reciprocations of the loading machine and in connection with the rope drum propelling mechanism is described and claimed in my co-pending application S. N. 370,204, filed Dec. 14, 1940, for an improvement in Loading machines.

65 Each of the aforesaid co-pending applications S. N. 305,803; S. N. 377,349; S. N. 379,475; S. N. 380,880; and S. N. 370,204, was filed as a division of the parent application S. N. 170,426.

In the present application I am directing the claims to combinations including the power transmission mechanism for operating the conveyor apparatus.

Obviously those skilled in the art may make various changes in the details and arrangement of parts without departing from the spirit and

scope of the invention as defined by the claim hereto appended, and I therefore wish not to be restricted to the precise construction herein disclosed.

Having thus described and shown an embodiment of my invention, what I desire to secure by Letters Patent of the United States is:

A loading machine comprising the combination with a base frame, of a discharge conveyor mounted on said frame, a gathering conveyor mounted on said frame, a motor on said base frame, a vertical power transmitting shaft, two gears connected to said shaft to rotate therewith, mechanism connecting said motor directly to said shaft through one of said gears, a third gear loose on said shaft, a gear train between the third gear and said gathering conveyor, a

clutch between said shaft and said third gear to control the operation of the gathering conveyor, said three gears and clutch being concentric with said shaft and compactly mounted in 5 advance of said motor, and power transmission mechanism between said discharge conveyor and the other of said two gears, said last-named power-transmission mechanism comprising a clutch for controlling the operation of said discharge conveyor, the construction and arrangement being such that by means of said clutches the said conveyors may each be operated independently of the other from the same vertical power transmitting shaft by a single motor connected thereto.

NILS D. LEVIN.
